DESIGN FOR A FLOOR MAT

Enoch E. Paine and Frank D. Adams, Cleveland Heights, Ohio, assignors to The Paine & Williams Company, Cleveland, Ohio, a corporation of Ohio

Application March 5, 1935, Serial No. 55,748

Term of patent 7 years

To all whom it may concern:

Be it known that we, Enoch E. Paine and Frank D. Adams, citizens of the United States, and residents of Cleveland Heights, county of Cuyahoga, and State of Ohio, have invented a new, original, and ornamental Design for Floor Mats, of which the following is a specification, reference being had to the accompanying drawing, forming a part thereof.

In said annexed drawing:—

Fig. 1 is a plan view of a floor mat embodying our design; Fig. 2 is a fragmentary plan view on an enlarged scale of a portion of the mat; Fig. 3 is a cross-sectional view, taken on the line 3—3 of Fig. 2; and Fig. 4 is a cross-sectional view, taken on the line 4—4 of Fig. 2.

We claim:

The ornamental design for a floor mat, substantially as shown.

Signed by us, this 1st day of March, 1935.

ENOCH E. PAINE.
